ABRASIVE BLAST

Herbert T. Blount, Los Angeles, Calif., assignor
to Mills-Alloys, Inc., Los Angeles, Calif., a corporation of Delaware

Application May 31, 1938, Serial No. 210,916

8 Claims. (Cl. 51—9)

This invention relates to an abrading device of the type wherein the abrasive is in granular or shot form, which is discharged from a wheel against the article to be abraded by centrifugal force, due to rotation of the wheel at a high speed.

In general, such abrading devices have been proposed and used in the past. The revolving wheel is usually provided with passages extending from the axis toward the periphery, through which the shot or other abrasive passes as the wheel is rapidly rotated. The abrasive may be fed to the inner ends of these passages by any suitable feeding device.

The abrasive particles are often of the type that has high specific gravity, such as hard steel or other materials. Since they leave the wheel periphery at great speeds for producing the required hammering effect upon the work to be cleaned or abraded, it has been found that the wheel is itself very quickly abraded or worn away. The passages become enlarged and the form altered to such an extent as to impede the attainment of optimum inertia effects.

It is accordingly a commonly accepted detriment in this type of abrader that replacement of worn out wheels is required frequently, as often as after one or two hundred hours of service.

It is one of the objects of this invention to obviate these frequent renewals by materially increasing the length of useful life of the wheel.

This object is accomplished by lining the passages for the abrading material with a wear resisting layer; for example, tungsten carbide.

It is another object of this invention to make it possible to use the same wheel for an indefinite, extended life, by providing renewable parts in the form of nozzles, that are subject to the normal wear.

It is another object of this invention so to arrange the nozzles or passages that the wheel distributes the abrasive material in a band much wider than the width of the wheel, so as to operate upon a larger exposed area of the work to be cleaned or abraded.

This invention possesses many other advantages, and has other objects which may be made more easily apparent from a consideration of one embodiment of the invention. For this purpose there is shown a form in the drawing accompanying and forming part of the present specification. This form will now be described in detail, illustrating the general principles of the invention; but it is to be understood that

this detailed description is not to be taken in a limiting sense, since the scope of this invention is best defined by the appended claims.

Referring to the drawing:

5 Figure 1 is an elevation of an abrading wheel, partly broken away;

Fig. 2 is a section on an enlarged scale as seen on plane 2—2 of Fig. 1;

10 Fig. 3 is a fragmentary elevation of the outer end of one of the nozzles; and

Fig. 4 is a sectional view of an installation showing the wheel arranged for use.

The wheel 5 includes a frame or head 6 secured to a rotary shaft 7. This frame 6 provides a central space or cavity 8 for the reception of the abrasive material, and a plurality of renewable nozzle structures 9 extend outwardly from this space to the periphery of the wheel. With the wheel rotating, any material fed into space 8 will be discharged through the nozzles by centrifugal force. The rotation is usually so fast that its peripheral speed is high, of the order of 10,000 feet per minute; and the abrading material is discharged through the nozzles 9 with great velocity.

25 The wheel 5 is shown as supported for rotation in the upper portion of a closed housing 10 (Fig. 4). This housing may be provided with a grate 11 some distance below the wheel, where the work to be abraded or cleaned is placed. The abrasive may be fed from any suitable source, as through a chute 12, discharging into a feeder 13, leading to the inner space 8 of wheel 5. This feeder 13 may include valving means, several forms of which are well known in the art, which feeds the abrasive to the central space 8 over only a limited sector of the plane of revolution of the wheel. By this means the angle through which the discharge occurs is limited approximately to the spread of the grate 11.

30 40 The abrasive is usually some finely divided hard material, which may or may not have sharp edges. Thus, small round pieces of steel, of the order of 20-mesh, known as "shot," may be used, or carbondum, or sand, or any of various other materials, depending on the work to be abraded. Since any abrasive likely to be used is hard enough to cause rapid wear of these wheels as usually constructed, they have an extremely short life.

45 50 55 In the present wheel, the parts which come in contact with the abrasive while under high velocities, are lined with a hard, wear resistant material, such as tungsten carbide. Further, since only the advancing part of the nozzle bore

is subject to wear by the discharge of the abrasive, the life of the nozzles can be increased by making provision to bring the unworn part of the nozzle bore into the advancing position. Also, by making the nozzles readily removable and replaceable, the wheel frame can be used indefinitely.

Referring to Figs. 1 and 2, the frame 6 comprises a pair of circular plates or flanges 16 and 17 appropriately secured to inner and outer rings 18 and 19. This may be accomplished for example by providing annular grooves in plates 16 and 17 for accommodating the edges of the rings 18 and 19, and welding over the adjacent parts of the rings and plates as indicated at 38 (Fig. 2). One of the plates as 16, has a central machined and counterbored area 20 into which is secured a hub 21, as by cap screws 22. The hub 21 is fastened in any suitable manner to shaft 7 to rotate therewith. The central space 8 is defined by ring 18 and plate 16, a central opening 23 in plate 17 being provided for the feeding mechanism 13. The ring 18 is provided with a plurality of equi-distant bores or openings 24, which may be midway between plates 16 and 17, to receive the nozzle structures 9.

Each nozzle structure 9 consists of an inner member or lining 26 made from some hard material that can resist wear, as tungsten carbide. The inner end 27 of the bore of the nozzle lining tapers outwardly, while the outer end of the bore is provided with flattened surfaces 28 (Fig. 3) at right angles to the plane of revolution. This configuration of the bore gives a better distribution of the abrasive. The nozzle 26 has an outer cylindrical jacket 29 of relatively soft metal, such as iron or steel, with its lower portion 30 of reduced diameter providing a shoulder 31. This jacket strengthens and protects the brittle lining 26.

A protecting thimble 32 fits over the end of the jacket 29 and against shoulder 31. Ring 19 is provided with bores 34, corresponding to bores 24, each having a counterbore 35 to receive flange 33. These thimbles 32 may be assembled on the ends of the nozzles 9 by being passed through any of the openings 39 (Fig. 1) in plate 17, after which they may be telescoped over the nozzle and then the nozzle may be inserted into aperture 34 in ring 19.

This arrangement securely holds the nozzle structure against displacement by centrifugal force; clamping means, such as set screws 36, are provided, engaging the nozzles 9 and preventing them from moving inwardly into space 8. These screws also restrain the nozzles against rotation about their longitudinal axis, so that the flat surfaces 28 at the end of the nozzle may be accurately set and maintained. By loosening set screw 36, the nozzle may be turned to bring another surface 28 in position when the first has been worn, or the nozzle may be removed and another one inserted.

To protect the inner surface of ring 18 from wear by the abrasive, the area between the nozzles is covered by a layer of resilient material 37, which may be soft rubber. To give a better distribution of the abrasive over the grate 11 supporting the work, adjacent nozzles 9 are purposely inclined slightly in opposite directions from the plane of rotation.

As shown most clearly in Fig. 4, this arrangement has the effect of staggering the nozzle openings. Nozzles thus staggered or inclined will "shoot" the abrasive particles farther toward the inclined direction; thus there is an effective spread of the abrasives in a direction parallel to

the axis of the wheel rotation, as indicated by lines 40.

What is claimed is:

1. A wheel of the character described including an inner ring, an outer ring, and front and back plates joining the rings, said back plate including means by which the wheel may be attached to a rotating support, a plurality of nozzles extending from the space within the inner ring through said rings substantially to the periphery of the wheel, adjacent nozzles diverging in opposite directions from the plane of rotation passing through their inner ends.

2. In apparatus of the character described, a rotary frame having side flanges and radially spaced rings between the flanges, the rings being joined to the flanges, one or more nozzles supported in said spaced rings, said rings being provided with aligned apertures for the accommodation of said nozzles for supporting them, and a member telescoping over one end of each nozzle and providing a flange to prevent removal of said nozzle through the corresponding aperture.

3. A wheel of the character described including an inner ring, an outer ring, and means joining said rings, the inner ring defining a space adapted to receive abrasive material, means forming a tubular nozzle extending from said space through the rings for discharging the abrasive, means forming a shoulder on the nozzle engaging one of said rings to restrain the nozzle against centrifugal force due to rotation of the wheel, and means adapted to clamp the nozzle in the wheel, said nozzle being so arranged that, upon loosening said clamping means, the nozzle may be turned about its axis to cause a different part of its bore to be in contact with the abrasive as the abrasive is discharged.

4. In a device of the character described, a rotary frame, a plurality of nozzle structures supported by the frame and angularly spaced from each other about the frame axis, and means detachably securing said nozzle structures in the frame, said means permitting the nozzle structures to be adjusted angularly about their axes, respectively without altering their positions in a radial direction, to bring different areas of the nozzle passages into contact with the discharged abrasive, and operating to secure said structures in any adjusted position.

5. In a device of the character described, a rotary frame, means forming a nozzle structure and having a shoulder upon which said structure is supported in the frame, and means to detachably secure said structure on said shoulder in the frame, said means permitting said structure to be adjusted on said shoulder to bring different areas of the nozzle passage into contact with the discharged abrasive, without altering the position of the structure in a radial direction, and operating to secure said structure in any adjusted position.

6. As an article of manufacture, a replaceable nozzle for a wheel of the character described, said wheel including a rim through which the nozzle extends, said nozzle including a lining of hard material and a reinforcing jacket of softer material, and a thimble of harder material than the jacket, said thimble being secured on the jacket and having a shoulder adapted to engage the rim and retain the nozzle in the wheel, as well as a skirt to protect that portion of the jacket outside the rim.

7. In a device for imparting motion to divided material, a rotary frame, and a series of nozzle

structures detachably supported on the frame and angularly spaced about the axis of the frame, said nozzle structures being of such length as to direct the discharge of said material, the inner ends of said nozzles being located in a common plane normal to said axis, adjacent nozzles being oppositely inclined with respect to said plane to increase the area over which the material is discharged.

8. In a device for imparting motion to divided 10

material, a rotary frame, and a series of nozzle structures detachably supported on the frame and angularly spaced about the axis of the frame, said nozzle structures being of such length as to direct the discharge of said material, the inner ends of said nozzles being located in a common plane normal to said axis, adjacent nozzles diverging in the direction of said axis, to increase the area over which the material is discharged.
